(57) CLAIM

The ornamental design for a rake, as shown and described.

DESCRIPTION

FIG. 1 is a left front perspective of a rake, showing my new design;

FIG. 2 is a front elevational view thereof;

FIG. 3 is a top plan view, thereof;

FIG. 4 is a side elevational view, the opposite side elevational view being substantially a mirror image, thereof;

FIG. 5 is a rear elevational view, thereof;

FIG. 6 is a bottom plan view, thereof; and,

FIG. 7 is a left front perspective view thereof, with the handle in an alternate extended position. Said handle is shown fragmented for ease of illustration.
